W. J. MINVILLE

LOOM HEDDLE FRAME

Filed Dec. 14, 1922

Inventor,
Wilfrid J. Minville
By: Keratius E. Bellows
Attorney

UNITED STATES PATENT OFFICE.

WILFRID J. MINVILLE, OF MANVILLE, RHODE ISLAND.

LOOM-HEDDLE FRAME.

Application filed December 14, 1922. Serial No. 606,945.

To all whom it may concern:

Be it known that I, WILFRID J. MINVILLE, a citizen of the United States, residing at Manville, in the county of Providence and 5 State of Rhode Island, have invented certain new and useful Improvements in Loom-Heddle Frames, of which the following is a specification.

My invention relates to heddle frames, 10 sometimes called "reeds," designed for leno weaving, and more particularly to the needles employed therein.

In leno frames it is common to forwardly offset between alternate dents broad needles 15 whose upper ends have a continuous unbroken bevel or incline extending the entire width of the needle shank forming a resultant apex with the offset needle portion. One of the pair of warp threads traverses a 20 needle eye while the second or disengaged warp thread is, by the harnesses, lifted over the needle point and then downwardly between its needle and its right hand adjacent dent, and is next elevated over the needle 25 point and then downwardly between its needle and its adjacent left hand dent, thus alternating characteristically of the leno weaving art. The described needle end permits the accidental escape of the disengaged 30 warp thread. Furthermore the point of the needle often becomes laterally bent so that its beveled edge either contacts with or inclines laterally towards an adjacent dent so that the disengaged warp thread is induced to reciprocate vertically at one side 35 of the needle, rather than to reciprocate alternately at both sides of the needle.

The essential objects of my invention are to overcome the above enumerated disadvantages.

To this end essentially my invention consists in such parts and in such combinations of parts as fall within the scope of the appended claims.

45 In the accompanying drawings which form a part of this specification—

Figure 1 is a fragmentary front elevation of a heddle embodying my invention,

50 Figure 2, a section of the same on line 2—2 of Figure 1,

Figure 3, an enlarged perspective view of the upper end of the needle, and

Figure 4, a like elevation of a needle and adjacent dents showing a thread engaging the needle. 55

Like reference characters indicate like parts throughout the views.

In the drawings 8 represents the heddle frame of any usual preferred construction including the common flat metallic dents or 60 separators 10 mounted therein. Located between the dents and fastened thereto at their lower ends in the frame are needles 12 which alternate with the dents. The needles are shorter than the dents and are 65 sufficiently broader than the latter to extend beyond and in front of the plane of the forward edges of the latter.

Each needle is of thin flat metal comprising a broad body portion 14 having upon 70 its upper end a vertical finger 15 formed in its forward lateral margin. The upper end 17 of the finger is downwardly and rearwardly beveled from the forward edge 18 of the needle forming an acute point 19. The 75 rear edge 20 forms an abutment or shoulder. Extending from the base of the finger 15 is a downwardly and rearwardly inclined shoulder 21 extending to the rear edge 22 of the needle. 24 is the usual needle eye 80 through which passes one of the two warp threads, not shown. The other or disengaged warp thread 26 is herein shown in full lines at one side of a needle, and in broken lines at the opposite side of the needle 85 in Figure 4.

It will be observed by reference to Figures 2 and 4 that the vertical finger 15 is parallel with the dents, and located in front thereof and spaced therefrom as at 27. Hence even 90 if the finger 15 becomes laterally bent it will not contact with the adjacent dent but the warp thread will pass through the space 27 and thence downwardly.

Furthermore the advanced finger 15 wholly 95 spaced from the dents forwardly thereof not only makes engagement of the thread certain, but acts as a positive guide which assists to force the thread down between the needle and dents. This enables the dents 100

to be set closer together and thus increases the number of dents possible in a single frame.

I claim:—

- 5 1. A heddle-frame having alternate dents and needles, each of said needles comprising a body provided with an inclined shoulder, and with an eye adjacent said shoulder, and a vertical finger upon the body above the shoulder in advance of the dents as and for the purpose set forth.
- 10

2. A heddle-frame having alternate dents and needles, each of said needles comprising a body provided with an inclined shoulder, and with an eye adjacent said shoulder, and a vertical finger integral with the body above the shoulder in advance of the dents with its rear edge parallel with the dents, as and for the purpose set forth. 15

In testimony whereof I have affixed signature. 20

WILFRID J. MINVILLE.
